UNITED STATES PATENT OFFICE.

EDWARD G. PRYOR, OF PUEBLO, COLORADO.

LOCK.

Application filed September 20, 1926. Serial No. 136,564.

The device forming the subject matter of this application is a permutation lock, and the invention aims to provide novel means whereby a bolt may be held through the instrumentality of a plurality of retainers, each of which is under the control of a permutation mechanism.

Another object of the invention is to improve the permutation mechanism.

10 It is within the province of the disclosure to improve generally and to enhance the utility of devices of that type to which the invention appertains.

With the above and other objects in view 15 which will appear as the description proceeds, the invention resides in the combination and arrangement of parts and in the details of construction hereinafter described and claimed, it being understood that 20 changes in the precise embodiment of the invention herein disclosed, may be made within the scope of what is claimed, without departing from the spirit of the invention.

25 In the drawings:

Figure 1 shows in front elevation, a lock constructed in accordance with the invention;

Figure 2 is an elevation wherein most of 30 the back plate has been removed, a part of the back plate remaining in section;

Figure 3 is an elevation showing the rear surface of the front plate, with sundry parts of the lock in such relation with respect to 35 each other as they will assume when the bolt is held in advanced position;

Figure 4 is a vertical transverse section of the lock;

Figure 5 is a view similar to Figure 3, 40 but showing the parts as they will appear when the bolt is free for sliding movement, parts being broken away in Figure 5;

Figure 6 is a perspective disclosing one 45 of the bolt holders which cooperate with the tumbler disks.

The lock comprises a frame which, in Figure 1, is designated by the numeral 1. The frame 1 includes (Figure 4) a front plate 2 and a back plate 3, spaced apart. 50 The back plate 3 is supplied at its lower edge with a thick bottom flange 4 which extends forwardly into contact with the front plate 2. Between the plates 2 and 3 is located the body 5 of the frame, the body 5 being in the form of a rectangular block, the outline of which appears to best advantage

in Figure 2. A securing element, such as a screw 6, shown in Figure 4, passes through the bottom flange 4 of the back plate 3 and is threaded into an opening 16 in the front plate 2. There are holes 7, (Figure 2) in the block-like body 5, and these holes 7 register with holes 8 (Figure 3) in the front plate 2. Securing elements 9, constructed like the screw 6, pass through the back plate 3, and through the holes 7 in the body 5, the forward ends of the securing elements 9 being engaged in the holes 8 of the front plate 2. Thus, the constituent parts of the frame 1 are held rigidly together.

Referring to Figure 2, it will be noted that the lower edge of the body 5 is spaced from the upper surface of the flange 4 to form a guideway 10, in which a lock bolt 11 is mounted for right-line reciprocation. The throw of the locking bolt 11 is limited by a lug 12 on the bolt which moves in a notch 14 formed in the upper edge of the bottom flange 4 of the back plate 3. The locking bolt 11 is advanced and retracted by hand, through the instrumentality of a headed stud 15 mounted at its inner end in the bolt, the stud being movable in a slot 17 in the front plate 2. The slot 17 is indicated in dotted lines in Figure 1. The slot 17 is closed by a cover piece 18 which is carried by the stud 15, between the head of the stud and the front plate 2. In order to keep the cover piece 18 from swinging on the stud 15 and exposing the slot 17, the lower edge of the cover piece 18 is caused to slide in engagement with the upper edge of a guide strip 19 mounted on the outer surface of the front plate 2. The locking bolt 11 is equipped in its upper edge 25 with a plurality of seats 20 and with a plurality of seats 21. The seats 21 come into play when the locking bolt 11 is advanced as shown in Figures 2 and 3, whereas the seats 20 function when the locking bolt 11 is retracted.

Referring to Figure 2, the reader will note that in the rear surface of the block-like body 5 there is a recess 22, the upper edge of which is marked by the numeral 23, because that edge of the recess has a function which will be described hereinafter. In the forward surface of the body 5 there is a chamber 24 of sufficient size to receive the several disk tumblers 27 shown in Figure 3. The body 5 has a forward recess 25, located below the chamber 24, and of sufficient size

to receive for vertical movement, the shifting bar 28 which is shown in Figure 3. The body or block 5 has a plurality of vertical guide slots 26. These guide slots 26 extend 5 entirely through the block 5, from front to back, and they open through the lower edge of the block, into the guideway 10, as disclosed in Figure 2. The guide slots 26 communicate also with the forward recess 25, 10 with the tumbler chamber 24, and with the recess 22.

The shifting bar 28 is supplied with a plurality of upstanding fingers 29, seen in Figure 3, the fingers being located at the ends 15 of the bar, and intermediate the ends of the bar. The shifting bar 28 is equipped intermediate its ends with a depending finger 30. The fingers 29 have a part in the operation of the locking mechanism, but the 20 finger 30 merely aids in giving the shifting bar 28 a smooth movement up and down on the inner surface of the front plate 2. The shifting bar 28 is moved up and down by a stud 31, secured in the bar, as shown in Figure 4, the stud having a head 32 disposed 25 in an accessible position outwardly of the front plate 2. The stud 31 operates in a vertically elongated slot 33 in the front plate 2. The slot 33 is closed by a cover piece 34 30 retained on the stud 31 by the head 32. A guide strip 35 (Figure 1) on the front plate 2, holds the cover piece 34 from swinging on the stud 31 and keeps the cover piece in place over the slot 33.

35 In the guide slots 26 of the body 5, latches or bolt holders 36 are mounted for vertical reciprocation, the bolt holders 36 being tapered at their upper ends, as shown at 37. The lower ends of the bolt holders 36 40 are received in the seats 21 (Figure 2) of the locking bolt 11, to hold the locking bolt advanced, and when the locking bolt 11 is retracted, the lower ends of the bolt holders 36 are received in the seats 20 of the bolt 45 11. Each of the bolt holders 36 is supplied in its forward surface with a recess 38 which receives the shifting bar 28 and its fingers 29, the fingers 29 cooperating with the bolt holders 36, at the upper ends of the recesses 50 38, to raise the bolt holders when the shifting bar is raised by means of the stud-head 32.

There are depressions 39 in the outer surface of the front plate 2. Dials 40 are inscribed upon the front plate 2, about the depressions 39. Tumbler shafts 41 are journaled in the body 5, concentrically with respect to the depressions 39. The tumbler shafts 41 are provided at their outer ends 60 with heads 42. The heads 42 retain the permutation disks 43 in the depressions 39. The permutation disks 43 are supplied with indices 44 adapted to cooperate with the dials 40. The tumbler shafts 41 are supplied with 65 projections 45 adapted to be received in

notches 46 in the permutation disks 43. The tumblers 27 (hereinafter mentioned) are mounted on the tumbler shafts 41 and have notches 47 at their centers, the notches being adapted to receive projecting pins 48 on the tumbler shafts. Here note that many permutations may be made, because the projections 45 on the tumbler shafts 41 may be engaged in any of the notches 46 of the permutation disks 43, and because any of the 70 projections 48 on the tumbler shafts 41 may be engaged in any of the notches 47 of the tumblers 27. Each of the tumblers 27 has many shallow notches 49 and one deep notch 50. The shallow notches 49 are dummy notches, in that when the tapered ends of the bolt holders 36 are received in the notches 49, the lower ends of the bolt holders still will be engaged with the seats 20 or 21 of the bolt 11, and the bolt cannot be thrown. The notches 49 are intended to deceive a person who is attempting to crack the lock by touch or sound. When, however, the bolt holders 36 move out of the seats 20 or 21 in the bolt 11, the ends 37 of the bolt holders are received in the deep notches 50 of the tumblers, and the bolt 11 can be shot. The holes 51 in the plate 2, through which the tumbler shafts 41 pass, are large enough to accommodate the pins 48, so that the tumbler shafts can be moved to the right in Figure 4, endwise, thereby permitting both the permutation disks 43 and the tumblers 27 to be adjusted circumferentially of the tumbler shafts to change the combination. A novel means is provided for holding the tumbler shafts 41 for rotation in the body 5 of the lock, and in the position delineated in Figure 4 of the drawings. Having this 95 consideration in mind, the tumbler shafts 41 are supplied near to their rear ends with circumferential grooves 52 defining reduced necks 53. A retaining bar 54 is located in the rear recess 22 of the body 5 and has in its lower edge notches 55 which receive the reduced necks 53 of the tumbler shafts 41. The retaining bar 54 obviously prevents the tumbler shafts 41 from being withdrawn endwise, and in order to hold the retaining bar 54 engaged with the necks 53 of the tumbler shafts 41, a locking piece 56 is inserted into the recess 22, the lower edge of the locking piece engaging the upper edge of the retaining bar 54, and the upper edge of the locking piece engaging the body 5 at the upper edge 23 of the recess 22. When the back plate 3 is taken off, the locking piece 56 may be picked out of the recess 22, it being possible, then, to raise the retaining bar 54 out of engagement with the rear ends 105 of the tumbler shafts 41, so as to permit circumferential adjustment of the permutation disks 43, and of the tumblers 27, to change 110 the combination.

In practical operation, the tumblers 27 130

are rotated by means of the shafts 41 and the heads 42 of the shafts, until the indices 44 on the disks 43 cooperate with the proper numerals of the dials 40, the deeper notches 50 of the tumblers 27 being brought immediately above the tapered ends 37 of the bolt holders 36. All of the holders 36 then can be raised out of engagement with the seats 20, or out of engagement with the 10 seats 21, in the bolt 11, this raising of the bolt holders 36 being brought about by lifting the shifting bar 28 through the instrumentality of the head 32, the fingers 29 of the bar 28 engaging the bolt holders 36 at the upper ends of the recesses 38 (Figures 6 and 4). When the bolt holders 36 are disengaged from the bolt 11, as aforesaid, the bolt may be moved endwise by means of the stud 15. When the bolt is in the advanced 15 position shown in Figure 3 the bolt holders 36 may be permitted to move downwardly, along with the shifting bar 28, the lower ends of the bolt holders being received in the seats 21 of the locking bolt 11, to hold 20 the locking bolt advanced. Then, by giving one or more of the tumbler shafts 21 a slight twist, the tumblers 27 will be rotated, and the deeper notches 50 will be so disposed with respect to the tapered ends of the bolt 25 holders 36, that the bolt holders cannot be raised out of engagement with the seats 21 in the locking bolt 11.

The locking bolt 11 is shown in Figure 2 as projecting beyond the left-hand end of the frame of the lock. The bolt 11, however, is capable of end-for-end reversal in the guideway 10, and may be so mounted that, when it is advanced, it will project beyond the right-hand end of the lock frame in 30 Figure 2.

What is claimed is:—

1. In a device of the class described, a frame, a locking bolt mounted for straight-line reciprocation on the frame, a bolt holder provided intermediate its ends with a recess, the bolt holder having straight-line movement on the frame, in a direction at right angles to the line of reciprocation of the bolt, into and out of engagement at 40 one end, with the bolt, a tumbler journaled on the frame and cooperating with the other end of the bolt holder to maintain the bolt holder in engagement with the bolt, the tumbler having an opening receiving said

other end of the bolt holder to permit the 55 first-specified end of the bolt holder to be disengaged from the bolt when the bolt holder is moved in one direction, and a shifting member mounted to move on the frame, the shifting member being movable in the 60 recess of the bolt holder to move the bolt holder in said direction.

2. In a device of the class described, a frame, a locking bolt mounted for straight-line reciprocation on the frame, a plurality 65 of bolt holders having parallel straight-line movement on the frame, in a direction at right angles to the line of reciprocation of the bolt, into and out of engagement with the bolt, tumblers journaled on the frame and cooperating with the bolt holders to maintain the bolt holders engaged with the bolt, the tumblers having openings in which one end of the bolt holders is adapted to be received, when the bolt holders are moved 70 in one direction, thereby to disengage the opposite end of the bolt holders from the bolt, and a shifting member movable on the frame and engaging all of the bolt holders to move them in said direction, the bolt 75 holders being movable with respect to the shifting member.

3. In a device of the class described, a frame, a tumbler shaft journaled on the frame, a tumbler on the tumbler shaft, locking mechanism cooperating with the tumbler, the tumbler shaft being provided with a circumferential groove, a retaining member engaged in the groove, and a locking 85 piece interposed between the retaining member and a part of the frame, and constituting means for holding the retaining member engaged in the groove.

4. In a device of the class described, a frame, a tumbler shaft journaled in the frame, a tumbler carried by the tumbler shaft, locking mechanism cooperating with the tumbler, the tumbler shaft being provided with a reduced neck, a retainer having a notch receiving the neck, and a locking 95 piece interposed between the retainer and a part of the frame and constituting means for holding the retainer engaged with the neck.

In testimony that I claim the foregoing 105 as my own, I have hereto affixed my signature.

EDWARD G. PRYOR.
